WOVEN WIRE SCREEN

Charles A. Scheeler, Buffalo, N. Y., assignor to
 Buffalo Wire Works Co., Inc., Buffalo, N. Y., a
 corporation of New York

Application November 16, 1935, Serial No. 50,207

8 Claims. (Cl. 139—425)

This invention relates to a woven wire screen and more particularly to a grain cleaning screen in which the shoot or weft wires are closely spaced and in which the warp wires are arranged in groups or strands, each composed of a plurality of contiguous warp wires to provide the necessary strength and the strands being spaced a substantial distance from one another so as to provide a screen having elongated openings in the direction of the shoot or weft wires. Such screens are generally, but not necessarily, also provided with hardened spring steel shoot wires, while the warp wires are of soft steel.

Serious difficulty has been encountered in weaving screening of this type, the principal difficulty being in the breaking of the warp wires during weaving. A further difficulty encountered was the tendency of the side warp wires of each strand to separate and slide outwards along the shoot wires. Heretofore such screening has been made in which the warp strands were composed of a single central warp wire flanked by an equal sized warp wire on each side and woven in opposition to the central wire. With this screen great difficulty was experienced during the weaving operation, the central warp wire of each strand breaking at frequent intervals. This was due to the fact that the combined force or pressure of the two flanking wires was exerted against this central warp wire, crimping it more sharply and putting it under excessive strain. In other words, each shoot wire would be offset toward the side embraced by the single central wire and this wire was under excessive strain. When a heavier central wire was used to compensate for this strain, the shoot wires distorted or crimped and the flanking wires slid outwardly along the shoot wires thereby resulting in separation of the wires of the strand. Since the screen mesh is elongated in the direction of the shoot wires, this separating tendency was very pronounced as compared with square mesh screening. This same result would occur if four warp wires were employed in the strand in alternation, i. e. the first and third wires and the second and fourth wires parallel with one another. Moreover, with this last form, the outside wires would not only spread but would do no work.

It is the object of the present invention to provide a screen having elongated mesh in the direction of the shoot wires, and having the warp wires arranged in strands composed of a plurality of wires, in which the warp wires are so woven that the strain is distributed equally among the several warp wires in each strand and in which there

is no tendency for the flanking warp wires of each strand to slide out because of the great distance between the strands.

In the accompanying drawing:

Fig. 1 is a plan view of a small section of a grain cleaning screen made in accordance with my invention.

Fig. 2 is a section, taken in the direction of the shoot wires along line 2—2, Fig. 1.

Figs. 3 and 4 are sections taken parallel with the warp wires along the correspondingly numbered lines on Fig. 1.

The grain cleaning screen shown consists of a plurality of shoot or weft wires 10 interwoven with strands 11 of warp wires by inserting the 15 shoot wires in the shed formed by the loom in the usual and well known manner. The shoot wires 10 are preferably made of hardened spring steel in grain cleaning screening but my invention can be practiced with other types of shoot 20 wires. The strands 11 of warp wires are spaced a very substantial distance apart and the shoot wires 10 are closely spaced so that the openings 12 in the screen are elongated in the direction of the shoot wires.

Each strand 11 of warp wires consists of four 25 separate wires arranged side by side, the central pair of warp wires 13 and 14 being flanked by side warp wires 15 and 16. The warp wires of each strand are identical in size and other characteristics. Each warp wire passes from one side of each shoot wire to the opposite side of the next succeeding shoot wire, in the usual and well known manner, and the central pair of warp wires 13 and 14 of each strand are woven parallel 30 with one another. The outside warp wires 15 and 16 are woven to pass on the opposite side of each shoot wire from that embraced by the central pair of wires 13 and 14 and therefore the outside wires 15 and 16 are disposed parallel with 35 one another.

It will also be noted that the corresponding 40 warp wires of successive strands are woven oppositely to one another. Thus with the top strand in Fig. 1, the outside warp wires weave over the first shoot wire 10 on the left, whereas the outside warp wires of the next strand 11 weave under this left shoot wire. This reduces the 45 tendency of the warp wires to deflect the long stretches of the shoot wires between the strands 50 11.

The warp wires composing the strands 11 are 55 all of the same size and it has been found that by weaving four wire warp strands in the manner shown there is no danger of breaking any of the 55

warp wires during weaving, nor is there any tendency for the side wires of the strands to slide out from the strand even with the elongated mesh shown.

5 With screening heretofore made with three wire strands and the outside wires alternating with the central wire, the combined force of the two outside wires against the central wire caused the central wire to break frequently during weaving. On substituting a larger central wire in 10 the three wire strands, the outside wires would slide out due to the long distance between the strands. Other arrangements of the wires of a four wire strand were also found wanting since 15 if the strand were composed of two pairs of parallel wires arranged side by side, the pairs would slide away from one another and if the four wires were woven in alternation with one another (the first and third and the second and 20 fourth wires parallel with one another) the outside wires would not only slide out, but also would do no work.

The four wire warp strands, woven in the manner shown, overcome the above objections 25 and provide a warp weave for screening having elongated mesh in the direction of the shoot wires which is easily woven, is not subject to breakage in use and in which the wires comprising the warp strands do not tend to separate.

30 I claim as my invention:

1. A woven wire screen composed of closely spaced shoot wires and interwoven strands of contiguous warp wires, the strands being spaced a greater distance from one another than said 35 shoot wires so as to provide openings which are elongated in the direction of the shoot wires, each of said strands being composed of a pair of central wires interwoven with the shoot wires parallel with one another and a side wire on 40 each side of said pair of central wires and engaging the side of each shoot wire opposite from that engaged by the central pair of warp wires.

2. A woven wire screen composed of closely 45 spaced hardened shoot wires and interwoven strands of contiguous warp wires, the strands being spaced a greater distance from one another than said shoot wires so as to provide openings which are elongated in the direction of the shoot wires, 50 each of said strands being composed of a pair of central wires interwoven with the shoot wires parallel with one another and a side wire on each side of said pair of central wires and engaging the side of each shoot wire opposite from that engaged by the central pair of warp wires.

3. A woven wire screen composed of closely 55 spaced hardened, spring steel shoot wires and interwoven strands of contiguous warp wires, the 60 strands being spaced a greater distance from one another than said shoot wires so as to provide openings which are elongated in the direction of the shoot wires, each of said strands being composed of a pair of central wires inter- 65 woven with the shoot wires parallel with one another and a side wire on each side of said pair of central wires and engaging the side of each shoot wire opposite from that engaged by the central pair of warp wires.

70 4. A woven wire screen composed of closely 70 spaced shoot wires and interwoven strands of contiguous warp wires, the strands being spaced a greater distance from one another than said shoot wires so as to provide openings which are

elongated in the direction of the shoot wires, each of said strands being composed of a pair of central wires interwoven with the shoot wires parallel with one another and a side wire on each side of said pair of central wires and engaging the side of each shoot wire opposite from that engaged by the central pair of warp wires, said warp wires all being of the same size. 5

5. A woven wire screen composed of closely spaced shoot wires and interwoven strands of 10 contiguous warp wires, the strands being spaced a greater distance from one another than said shoot wires so as to provide openings which are elongated in the direction of the shoot wires, each of said strands being composed of a pair 15 of central wires interwoven with the shoot wires parallel with one another and a side wire on each side of said pair of central wires and engaging the side of each shoot wire opposite from that engaged by the central pair of warp wires, 20 said warp wires being identical in form and composition.

6. A woven wire screen composed of closely spaced shoot wires and interwoven strands of 25 contiguous warp wires, the strands being spaced a greater distance from one another than the shoot wires so as to provide screen openings which are elongated in the direction of the shoot wires, each of said strands being composed of 30 four wires, the central pair of which pass alternately on opposite sides of the successive shoot wires parallel with one another and each outside wire engaging the side of each shoot wire opposite from that engaged by the central pair 35 of warp wires, said warp wires being of the same cross sectional size so that the strain is distributed evenly among them and the side wires do not tend to separate from the strand.

7. A woven wire screen composed of closely 40 spaced shoot wires and interwoven strands of contiguous warp wires, the strands being spaced a greater distance from one another than said 45 shoot wires so as to provide openings which are elongated in the direction of the shoot wires, each of said strands being composed of a pair of central wires interwoven with the shoot wires parallel with one another and a side wire on each side of said pair of central wires and engaging the side of each shoot wire opposite from 50 that engaged by the central pair of warp wires, the several strands being so woven that the corresponding wires of successive strands engage the opposite side of each shoot wire.

8. A woven wire screen composed of closely 55 spaced shoot wires and interwoven strands of contiguous warp wires, the strands being spaced a greater distance from one another than the 60 shoot wires so as to provide screen openings which are elongated in the direction of the shoot wires, each of said strands being composed of four wires, the central pair of which pass alternately on opposite sides of the successive 65 shoot wires parallel with one another and each outside wire engaging the side of each shoot wire opposite from that engaged by the central pair of warp wires, said warp wires being of the same cross sectional size so that the strain is distributed evenly among them and the side wires do not tend to separate from the strand, 70 the several strands being so woven that the corresponding wires of successive strands engage the opposite side of each shoot wire.
